UNITED STATES PATENT OFFICE.

EUSTACE CAREY, HOLBROOK GASKELL, JR., AND FERDINAND HURTER, OF
WIDNES, COUNTY OF LANCASTER, ENGLAND.

MANUFACTURE OF BICARBONATE OF SODA.

SPECIFICATION forming part of Letters Patent No. 276,990, dated May 1, 1883.

Application filed July 24, 1882. (No model.) Patented in England November 16, 1881, No. 5,024.

To all whom it may concern:

Be it known that we, EUSTACE CAREY, HOLBROOK GASKELL, Jr., subjects of the Queen of Great Britain, and FERDINAND HURTER, 5 Ph. D., a citizen of Switzerland, and residing respectively at Widnes, in the county of Lancaster, England, alkali manufacturers, have invented certain Improvements in the Manufacture of Bicarbonate of Soda, (for which we 10 have obtained a patent in Great Britain, No. 5,024, dated November 16, 1881,) of which the following is a specification.

This invention relates to the manufacture of bicarbonate of soda from that form of crystallized carbonate of soda commonly known as "salts," the same being obtained during the "salting down" or evaporation by heat of solutions of carbonate of soda. These salts are, 15 essentially, a monohydrated carbonate of soda, although the degree of hydration may vary slightly, according to the temperature and other conditions in the salting-down operation.

The invention consists in subjecting the 20 said salts with agitation to the action of carbonic acid and in regulating or controlling the amount of moisture in the compound, removing any excess, and supplying any deficiency as may be required, whereby a uniform dry bicarbonate may be obtained from said salts 25 at one operation. During the process the surplus heat is removed to avoid the production of too high a temperature.

Heretofore it has been proposed to carbonate the monohydrated carbonate of soda by 30 exposing the same on frames to a current of carbonic acid; but in this process there is no agitation of the carbonate, nor any regulation or control of the moisture in the compound, as in the present invention. It has also been 35 proposed to carbonate salts and other carbonates of soda by exposure to carbonic acid with agitation; but in this process there is not only no regulation or control of the supply of moisture to one equivalent, so as to obtain a dry bi- 40 carbonate, but, on the contrary, water is to be added whenever the amount thereof is less than half the weight of the carbonate, so the bicarbonate produced will necessarily be a moist article. The process is, however, mainly 45 designed for the purification of soda. The

ordinary method of preparing the carbonate by carbonating soda crystals results in the production of a moist bicarbonate, (owing to the amount of water of crystallization,) which has to be dried for use at considerable trouble 55 and often loss.

The invention further comprises a new apparatus, which is or may be used in carrying the improved process into effect.

In carrying out our invention we find it advantageous to employ an apparatus such as is illustrated in side elevation, end view, and plan, respectively, in Figs. 1, 2, and 3 of the accompanying drawings. The iron cylinder A, of convenient size, is capable of being rotated 60 upon a horizontal axis. We find it convenient to make the cylinder A of about eight feet in length by five and a half feet in diameter. A cylinder of that size will hold a charge of about thirty hundred-weight of salts and produces therefrom about forty hundred-weight of 65 bicarbonate. The cylinder A is provided with hollow trunnions or axes supported by and capable of turning in bearings a, carried by a suitable frame-work. The hollow axis at the 70 one end of the cylinder is used for admitting carbonic-acid gas, and that at the other end is used for permitting the exit, when desirable, of any superfluous moisture, the hollow axles are continued into the interior of the cylinder 75 and deflected upward, as shown at b in Fig. 1, for the purpose of avoiding the lodgment therein of solid material and the consequent stoppage of the free passage of the gas into or from the cylinder.

We find it advisable to have apertures at e e in the cylinder A and exit-pipe C, respectively, which can be closed air-tight in any convenient manner, and through which, when necessary, the part of the exit-pipe C which is 80 inside the cylinder A may be cleaned easily and freed from dust, which is sometimes deposited there. Outside the cylinder A the exit-pipe C is carried upward at c² to a suitable height, and is then returned downward and 85 connected by the branch c³ with the pipe c⁴, by which the carbonic acid enters at the other end of the cylinder A. We find that when the pipe C is carried upward at c² about thirty feet the 90 difference of temperature, and consequently 95 100

the specific gravity, between the gas in the upcast and that in the downcast of the pipe C is such that a circulation of gas can be commenced and maintained when desired through 5 the pipe C, whereby the moisture which escapes from the salts during the process is conveyed away from the cylinder A and is condensed in the pipes, and may be collected and run off through a lute, x, or otherwise, the sur- 10 plus carbonic-acid gas returning to the cylinder by the branch c³. Fig. 4 shows a lute drawn to a larger scale. If at any time this circulation does not commence when desired, we open for a few moments a tap provided for the pur- 15 pose at the bottom of the downcast pipe above the lute. By doing this circulation is at once set up in the pipe C, and when commenced continues as long as it is required. The cylinder A is provided with openings for inserting 20 and withdrawing the matter to be or having been treated therein, close covers being provided to fit over these openings.

Having described one form of apparatus by which our invention may be performed, we now 25 proceed to describe the method of working which we find to give the best results.

The charge of salt introduced in the cylinder A is closed and made to revolve slowly through the intervention of a pulley and spur-gearing G, driven by any suitable motor. We 30 find from two or six revolutions per minute are sufficient. Carbonic-acid gas is turned on or admitted into the interior of the cylinder A by the pipe y. The temperature of salts or 35 carbonate of soda rises, and the carbonic-acid gas is rapidly absorbed by the charge. The progress of the operation may be ascertained by withdrawing and testing a sample from time to time. We find, however, that with a regular 40 and sufficient supply of pure or almost pure carbonic acid the operation is so uniform that after a short experience sampling and testing are unnecessary, the state of the carbonating material constituting the charge being inferred 45 with sufficient accuracy by noting the temperature of the cylinder, or even only the length of time that the operation has been in progress. When absorption decreases the temperature falls, and we find in practice that about five or 50 six hours are sufficient to complete the operation, and that at the end of two or three hours, or at the expiration of about one-third of the time necessary to complete the operation, it is advisable to commence drawing off the super- 55 abundant moisture. The operation will then proceed satisfactorily, and the resulting bicarbonate will in due time be completely finished, and will be found dry and of great purity and ready, when cold, for immediate grinding and 60 dressing.

The details of the foregoing operation will vary with circumstances, and will depend upon the character of the salts and the amount of moisture they contain. If and when the salts 65 are too dry, or become so during the operation, it is necessary to add water, this we prefer to do by adding steam to the carbonic acid. We

pass the carbonic acid, before it reaches the inlet-pipe y, to the cylinder A through a small tower, D, contiguous to the cylinder, and filled 70 with coke or other suitable material, into which the requisite quantity of steam is passed. This causes the carbonic acid to enter the cylinder A saturated or sufficiently saturated with moisture for the purpose. We find a very 75 small tower sufficient. A cylinder three feet diameter and four or five feet high is sufficient for the purpose. Water may also be added to the salts by injecting a fine spray of water into the cylinder A. If and when dilute carbonic 80 acid is employed—such as that resulting from the combustion of anthracite or coke—where an inert gas or gases are present, it is advisable to have two or more cylinders A connected together and so arranged that the inert gas or 85 gases may be permitted to escape without undue loss of carbonic acid. We effect this by having a series of two or more cylinders of convenient size, and passing the exit-gas from one cylinder into the next, and so on to the 90 last, the inert gas or gases being allowed to escape freely from the last cylinder of the series. Between each of the cylinders a gas-drying apparatus and a gas-moistening apparatus may be placed, and the exit gas or gases 95 from the one cylinder dried or moistened, as required, on its or their way to the next cylinder. The gas-pipes can be so arranged, as is well understood, that any one cylinder of the series can be isolated for filling or emptying or other 100 purpose. Fig. 5 represents in plan an arrangement of apparatus for this purpose. According to this arrangement three cylinders, A' A² A³, are employed, which are essentially of the same construction as represented by Figs. 1, 2, and 105 3. Each of them is capable of revolving independently of the others, suitable gearing, G, being provided for such purpose. The plan shows one method of connecting three cylinders so that any one of them may be isolated, and 110 this method can easily be adapted to any number of such cylinders. The carbonic-acid gas from any source enters the distributing apparatus H by the central pipe, y. This distributing apparatus consists of a cylindrical vessel, 115 through the bottom of which pass water-tight the central inlet-pipe, y, and three pairs of pipes arranged in a circle round this inlet-pipe, each pair being connected with the inlet and outlet of one of the cylinders A' A² A³, respectively. The cylindrical vessel H contains a sufficient depth of water to resist the pressure or suction, if any, of the gas. The open 120 ends of the pipes reach above the level of the water a distance at least equal to the depth of 125 the water in the vessel. Movable bent pipes are provided to slip over and connect any one of those pipes with any other.

The drawings represent the whole of the three cylinders A' A² A³ connected in the following manner: The central inlet-pipe, y, is connected to the pipe y' by a movable arm, c⁴, so that the carbonic acid may pass to the moistening apparatus D' and enter into the cylinder 130

A'. The gas passing out by the pipe c' (which is of sufficient length to cool the gas and condense excess of moisture, or, if not of sufficient length, may be carried upward and downward a suitable distance for the purpose) returns to the distributing apparatus H , where pipe c' is connected to pipe y^2 by a movable arm, c^4 . The gas thus is caused to pass to the moistening apparatus D^2 , from there to the cylinder A^2 , and returns by the pipe c^2 to the distributor, where the pipe c^2 is connected to the pipe y^3 by another movable arm. The gas finally passes through the moistening apparatus D^3 and cylinder A^3 , returns once more to the distributor H by pipe c^3 , and thence it may be allowed to escape by the ring-pipe z and outlet z^2 . If any water condenses in any of the pipes, it is allowed to escape through a lute similar to that represented in Fig. 4. If any of the moistening apparatus is not required for moistening purposes, the steam is not turned on thereto. Fig. 6 shows a section of the distributing apparatus. The drawing shows pipe c^3 connected by a movable arm, c^4 , to the pipe z , forming a complete ring round the distributing apparatus H . This ring-shaped pipe has four branches, $z^1 z^2$. Three of these branches, z^1 , are placed opposite the termini of the pipes $c' c^2 c^3$, respectively, and serve to connect, by means of the arms c^4 , any one of these pipes to this ring z . The fourth branch, z^2 , of the ring z is connected either to a chimney or an exhauster, which removes the inert gases. All these branches of the pipe z not in actual use are covered with a lid, as at z^3 . All connections are luted with water, as is well understood.

Having now described the nature of our in-

vention and the means whereby we carry it into effect, we desire to point out that we do not confine ourselves to the above-described or to any particular form of apparatus; but that

What we claim as novel is—

1. The manufacture of bicarbonate of soda by the employment and treatment, as hereinbefore described, of what have been hereinbefore referred to as "salts," and hereinbefore defined, by subjecting said salts to the action of carbonic-acid gas, the salts being mechanically agitated and the superabundant heat being removed, the moisture generated being drawn off, when in excess, and moisture being supplied when required, all substantially as hereinbefore described.

2. In the manufacture of bicarbonate of soda, the production of a circulation of the carbonic acid through the containing-vessel and through condensing-pipes for removing the absorbed moisture from the carbonic acid, substantially as described.

3. The combination, with the revolving cylinder, of the exterior circulating and condensing pipes connected with said cylinder, substantially as described.

In testimony whereof we have signed our names to this specification in the presence of two subscribing witnesses.

EUSTACE CAREY.
